UNITED STATES PATENT OFFICE.

FRED LIPS, OF ARLINGTON HEIGHTS, ILLINOIS.

MOLDER'S FLASK.

SPECIFICATION forming part of Letters Patent No. 714,207, dated November 25, 1902.

Application filed July 14, 1902. Serial No. 115,534. (No model.)

To all whom it may concern:

Be it known that I, FRED LIPS, a citizen of the United States, residing at Arlington Heights, in the county of Cook and State of Illinois, have invented certain new and useful Improvements in Molders' Flasks, of which the following is a specification, reference being had to the accompanying drawings.

My invention relates to improved fastening and hinging devices for molders' flasks and similar articles; and its object is to provide means by which one member of the flask may be separably hinged to the other member, so that it may be lifted therefrom and maintained in a fixed lifted position and at the same time may be entirely removed when desired and by which the two members of the flask or similar article may be automatically locked in position when brought together. I accomplish this object as hereinafter specified and as illustrated in the drawings.

That which I regard as new will be set forth in the claims.

Referring to the drawings, Figure 1 is a top or plan view of the cope placed upon the drag. Fig. 2 is a section on line 2 2 of Fig. 1. Fig. 3 is a section on line 3 3 of Fig. 1. Fig. 4 is an enlarged detail, being an isometric view of one of the front locking devices. Fig. 5 is an enlarged detail, being a vertical section of the front locking-lever. Fig. 6 is a sectional view of part of the flask shown in Fig. 2, showing the upper portion raised and held in an upright position; and Fig. 7 is an enlarged detail, being an isometric view of the rear locking and hinging mechanism.

In the drawings, 8 represents the lower part or drag of the flask, and 9 the upper part or cope. The drag 8 is provided upon one side with the projecting lugs or ears 10. (Best shown in Figs. 1 and 3.) The outer ends of the projecting lugs 10 are rounded into circular form and are provided with V-shaped notches 11. (Best shown in Figs. 1 and 3.) The cope or upper part of the flask is provided upon the corresponding side with lugs or ears 12, the lower part of each of which is rounded in the arc of a circle and provided with an edge to rest within the V-shaped slot 11 of the lugs 10. The centers of the circles on which the ends of the lugs 10 and the bottom surfaces of the lugs 12 are formed are on

the line of the top surface of the drag projected, as is best shown in Fig. 3. The edges of the lugs 12, bearing in the V-shaped grooves of the lugs 10, afford a bearing on which the parts turn when the cope is lifted to the position shown in Fig. 6 and form a part of the rear hinging mechanism of the flask. Upon the same side of the drag, which I will call the "rear," are two other lugs 13, which project outwardly therefrom. Each of the lugs 13 is provided with a suitable slot at its rear end, in which is pivoted a lever 14. The levers 14 are each provided with a shoulder 15, which projects inward toward the flask above the lug 13, and the lever is provided at its lower end with a projection 16, which is adapted to bear against the rear surface of the lug 13 and limit the backward motion of the lever 14. Each of the levers 14 is provided with a slot 17, which extends through the lever 14 to receive and engage the parts hereinafter described. The upper end of the lever 14 is preferably provided with a beveled shoulder 18 for the purpose hereinafter described. Upon the rear side of the cope are provided projecting arms 19, the outer ends of which are adapted to rest within the slots 17 in the levers 14 and to be engaged thereby. Upon each side of their ends the arms 19 are cut away, so as to provide rounded shoulders 20, as is best shown in Fig. 7. The lower part of the arms 19 is adapted to bear upon the upper surfaces of the shoulders or projections 15 for the purpose and in the manner hereinafter described. The ends of the arms 19 are beveled downward and inward in order to form a secure resting-surface for the ends of those arms when the upper part of the flask is lifted into the position shown in Fig. 6, as hereinafter described.

Upon the front side of the drag are ears 21, which are provided with a suitable opening to receive guide-pins 22, which are mounted in lugs 23 on the front surface of the cope 9. 24 indicates lugs which project forward from the front surface of the drag 8 and are similar in shape to the lugs 13 upon the rear side of the drag. They are slotted at their forward ends to receive each a lever 25, which is pivoted in said slot. The levers 25 are provided with a downward-projecting portion 26 below the pivot thereof in order to form a

stop to limit their outward movement, as is best shown in Fig. 3. The levers 25 are provided with an inward-projecting shoulder 26 above the pivotal point of said levers, which 5 when the levers 25 are in position projects inward toward the flask. The levers 25 are also provided with slots 27. (Best shown in Figs. 4 and 5.) The slot 27 passes completely through said lever and has its upper portion beveled upward and inward, as is best shown in Fig. 5. The slot is of such size as to receive and engage forward-projecting arms 28, secured to the front surface of the cope 9. These forward-projecting arms are 10 cut away on each side, so as to form a projecting portion 29, which is beveled downward and outward and is of suitable size to enter into and engage the slot 27 of the lever 25. The upper ends of the levers 25 are beveled downward and inward in order that said levers may be certainly thrown backward in proper position when engaged by the arms 28 when the cope is being closed upon the drag, as hereinafter described, and the outer ends 15 of the arms 28 are beveled upward and inward in order to assist in the throwing outward of the levers 25 when the cope is being lifted from the drag, as hereinafter described.

When it is desired to put the two parts of 30 the flask together, the ends of the arms 19 are inserted in the slots 17 of the levers 14 and the lugs 12 brought to bear upon the V-shaped grooves 11 of the lugs 10. If the parts are then lifted into the position shown in Fig. 6, 35 the top surface of the arms 19 will engage with the upper ends of the levers 14, the lower ends of said arms 19 resting within the slots 17 and bearing along their lower surfaces on the shoulders 15 and the levers 14. The levers 14 40 being prevented from going any farther back by the stops 16, the parts will remain in this position as long as it is desired. When it is desired to close the two parts together, the cope is swung downward upon the bearings 10 11 45 12. As it descends the lower surfaces of the arms 19 come in contact with the upper surface of the shoulders 15 just before the flask closes in the position shown in Fig. 2, forcing said shoulders downward, and consequently 50 rocking the levers 14 inward, causing the slot 17 to engage with the upper surface of the arms 19 and preventing a separation of the parts when brought together by vertical lifting of the same. At the same time as the 55 cope descends the front ends of the arms 28, as shown in dotted lines in Fig. 3, engage the beveled surfaces of the levers 25, which have been previously thrown back in order to free the parts, as hereinafter described, and insure 60 the levers 25 being thrown back into the position shown in dotted lines in Fig. 3. As the cope descends still farther the forward ends 29 of the arms 28 enter the slots 27 of the levers 25, and as the descent continues 65 farther the lower surfaces of the arms 28 bear upon the shoulders 26 of the levers 25, rocking the same inward into the position shown

in solid lines in Fig. 3, whereby the parts will be locked together, the slots 27 of the levers 25 engaging the projecting ends 29 of the arms 28 in the position shown in Figs. 4 and 3. The two members of the flask are thus locked together and cannot be separated by vertical lifting and without disengaging the front locking devices. 75

When it is desired to rock the cope back upon the drag, either to entirely disengage them or to separate them, the front levers 25 are pulled backward by hand. The cope may then be turned backward upon the drag upon 80 the bearings 10 11 12. As the movement continues the rounded shoulders 26 bear upon the inner surfaces of the lever 14 until when the parts are lifted into the position shown in Fig. 6 they will maintain that position, as 85 hereinbefore described.

I have shown and described my invention as applied to molders' flasks, and it is particularly adapted to this purpose. It is obvious, however, that the same devices for separably 90 hinging and fastening might be used on other articles than molders' flasks, in which it was desired to separably hinge two parts together and secure them in position, and I therefore do not confine my invention to such flasks, 95 except as hereinafter specifically claimed. It is also to be noticed that while I have described my invention as applied to molders' flasks adapted to have one part separately hinged upon the other so as turn thereon my 100 fastening devices might be used upon a flask which was not so hinged, but in which the cope was designed to be lowered directly upon the drag, in which case the bearings 10 and 12 might be omitted. In such case the levers 105 14 and 25 would be thrown backward to give clearance and the cope lowered directly upon the drag. The arms 19 and 28 as the cope is lowered would in such case contact, respectively, with the shoulders 15 and 26, throwing the respective levers into such position 110 that the slots in said levers would engage the ends of the arms and lock them firmly in position. I therefore do not confine my invention so far as it relates to said fastening devices to hinged flasks, except as specifically 115 claimed.

That which I claim as my invention, and desire to secure by Letters Patent, is—

1. The combination with two separably-hinged members having bearings on which said members may pivot, of an arm projecting from the hinged side of one of said members, and a lever pivoted on the hinged side of the other member in register with said arm 125 and provided with means to engage said arm and with a projecting shoulder adapted to be engaged by said arm when said members are closed one upon the other and throw said lever into engagement with said arm, substantially as described.

2. The combination with two separably-hinged members having bearings on which said members may pivot, of levers pivoted to

the hinged side of one member and provided each with an inward-projecting shoulder and with a slot, and arms, projecting from the hinged side of the other member in register with said levers, adapted to enter said slot and when said members are closed upon one another to engage said shoulders and automatically throw said levers into position where said slots will engage said arms, substantially as described.

3. The combination with two separably-hinged members having bearings on which said members may pivot, of levers pivoted to the hinged side of one member and provided each with an inward-projecting shoulder and with a slot, arms, projecting from the hinged side of the other member in register with said levers, adapted to enter said slot and when said members are closed upon one another to engage said shoulders and automatically throw said levers into position where said slots will engage said arms, levers pivoted to one of said members upon the side opposite the hinged side, said levers being provided with an inward-projecting shoulder and a slot, and arms projecting from the other of said members on the side opposite from the hinged side and in register with said levers, and adapted when said members are closed to contact the shoulders on said levers and automatically throw them into position where said slots will engage said arms, substantially as described.

4. In a separably-hinged molder's flask, the combination with a first flask member, of bearings on one side thereof, levers pivoted to said member on the same side as said bearings and provided each with a projecting shoulder and a slot, a second flask member provided with bearings adapted to engage the bearings on said first member and form a pivot on which one of said members may turn on the other, and provided on the same side with projecting arms adapted to enter the slots in said levers and when said members are closed together to contact said shoulders and throw said levers into position where the slots thereof will engage said arms, substantially as described.

5. In a molder's flask, the combination with a drag having bearings on one side and a cope having corresponding bearings adapted to en-

gage the bearings on said drag and form a pivot on which said cope may turn, of levers pivoted on the front and back of said drag and provided each with a slot and an inward-projecting shoulder, and projecting arms upon the corresponding sides of said cope, in register with said levers and adapted to enter said slots and when said members are closed to engage said shoulders and throw said levers into position where the said slots will engage said arms, substantially as described.

6. The combination with two separably-hinged members, of levers pivoted to one of said members and provided with stops to limit their outward motion, and each provided with a slot and an inward-projecting shoulder, of arms, projecting from the hinged side of the other of said members in register with said levers, adapted to have their ends enter said slots and having their ends beveled to correspond with the position of said shoulder when said levers are moved outward to the limit of their motion and to engage said shoulders and the ends of said levers above the slots, whereby said second member may be supported in a substantially vertical position upon said first member by means of the engagement of said arms with said shoulders and said levers, said arms being also adapted when said members are closed to engage said shoulders and automatically throw said levers into engagement with said arms, substantially as described.

7. In a molder's flask, the combination with two flask members, of levers hinged upon opposite sides of one of said members, and provided each with an inward-projecting shoulder and a slot, and projecting arms on opposite sides of the other member, in registry with said levers when said members are placed in position one upon the other, said arms being adapted to enter the slots in said levers and to engage the shoulders on said levers when one flask member is lowered upon the other, and throw said levers into a position in which said arms will engage with said slots, substantially as described.
